UNITED STATES PATENT OFFICE.

JOSEPH DELA MAR, OF POUGHKEEPSIE, ASSIGNOR TO THE CHAMPION
TOBACCO MACHINE COMPANY, OF NEW YORK, N. Y.

CIGAR-BUNCHING MACHINE.

SPECIFICATION forming part of Letters Patent No. 498,844, dated June 6, 1893.

Application filed January 4, 1892. Serial No. 416,954. (No model.)

To all whom it may concern:

Be it known that I, JOSEPH DELA MAR, of Poughkeepsie, county of Dutchess, and State of New York, have invented a certain new and useful Improvement in Cigar-Bunching Machines, of which the following is a specification.

This invention relates to machines for bunching or forming tobacco as cigars preparatory to applying the wrapper and it consists in the construction and novel arrangement of parts as hereinafter set forth.

In connection with this case reference may be had to my Patent No. 461,072, of October 13, 1891, in which certain clutch mechanism described and shown in this application is shown and claimed.

In the accompanying drawings, Figure 1, is a front elevation of a machine embodying my improvement. Fig. 2, is a side elevation with certain parts omitted. Fig. 3, is an enlarged plan of a portion of the machine showing it in its first position. Fig. 4, is similar to Fig. 3, but showing the parts in a second position. Fig. 5, is similar to Figs. 3 and 4, but showing the third position. Fig. 6, is a section through the line 6, 6, of Fig. 3. Fig. 7, is a section through the line 7, 7, of Fig. 4. Fig. 8, is a section through the line 8, 8, of Fig. 5. Fig. 9, is an enlarged detail side view. Fig. 10, is a transverse section through the top of the machine parallel with and looking toward the front of the machine. Fig. 11, is a transverse section through a feeder and table. Fig. 12, is a side elevation of a feeder mechanism. Fig. 13, is a top or plan view thereof. Fig. 14, shows a tobacco receiver. Fig. 15, shows a tobacco bunch and its line of cut by the formers. Fig. 16 shows an enlarged detail view of parts of the feeding mechanism, and Fig. 17 shows a longitudinal central section of the trough, bands and carriers of the feeding mechanism.

I will first describe the bunching mechanism, and then describe means for feeding tobacco filler thereto.

Referring by letter to the drawings, A designates a table supported by legs or uprights A' which have suitable cross-bars for supporting rotary parts of the machine. I will term

the parts A, A', and the cross-bars the main frame of the machine.

A² is a band or power wheel loosely mounted upon but adapted to rotate a shaft a, when a certain clutch mechanism is thrown into engagement, and operate the machine. The shaft a has a bearing at one end in the main frame of the machine and at the other end in a bearing on a pillow block a'. A pinion a³ is rigidly mounted on the shaft a and has on or adjacent to it, one member of a clutch a⁴. The other member of the clutch a⁴ is attached to the pulley A², and is movable with said pulley into engagement with the other member of the clutch by means of a lever A⁵ bifurcated at its upper end and engaging in an annular groove of the movable section of the clutch. At its lower end the lever A⁵ is attached to a rock shaft a⁶ having bearings in the main frame and provided with a treadle lever a⁶. Obviously by a downward movement of the treadle a⁶ the pulley A² and its clutch section will be moved longitudinally of the shaft a and into engagement with the clutch section on the pinion a³. The pinion a³ meshes with a gear wheel A⁴ secured to a shaft a⁷.

As a means for unlocking the clutch sections when the lever a⁶ is released by the foot of the operator I employ a yielding arm a⁸ which is secured at its lower end to the rock shaft a⁶ and projecting at its face end into the path of a lug a⁹ on the gear wheel A⁴. As long as the operator's foot holds down the lever a⁶ the arm a⁸ will yield and pass over the lug a⁹ but upon releasing the lever a⁶ the lug will move the arm a⁸ and through it the rock shaft a⁶ and clutch arm A⁵. This clutch operating mechanism is shown more in detail in my Patent No. 461,072, of October 13, 1891.

B is a gear wheel on the main shaft a⁷. This gear wheel B is not toothed throughout its entire circumference, but the teeth extend about half the circumference, or in other words, it has sufficient teeth to impart a complete revolution to a pinion b at a partial revolution of said gear B. The pinion b is mounted on a shaft b' having bearings in the main frame and at one end the shaft b' is provided with a crank B². A link b³ has at one end an

adjustable connection with the crank b^2 and at the other end is pivotally connected to a lever c connected to a rock shaft c' having bearings in hangers on the main frame. Arms 5 b^4 on the shaft c' have link connections b^5 with a carriage B' which is movable on a track on the table A for a purpose hereinafter set forth.

B^3 designates a mutilated gear wheel on the 10 main shaft a^7 to impart movement to certain reciprocating dies hereinafter set forth. This gear and its connections are shown more clearly in Fig. 9. It has opposite segmental rows of teeth b^9 , each row having a sufficient 15 number of teeth to impart a half revolution to a pinion B^4 having bearings in the main frame. The pinion B^4 carries a crank arm b^{10*} to which a lever B^5 is adjustably attached. At its outer end the lever B^5 is pivotally connected 20 to a rock lever B^6 fulcrumed at about its middle to a hanger on the main frame. At the upper end the rock lever B^6 has pivoted to it one end of an adjustable pitman rod B^7 which at the other end is pivoted to the die 25 frame B^8 . It will be seen by this construction that one row of teeth b^9 when engaged with the pinion B^4 imparts a forward movement to the die frame B^8 and the other row when engaged with said pinion B^4 completes 30 its revolution and imparts a return movement to the die frame B^8 . Of course when neither row of teeth b^9 is engaged with the pinion B^4 the said pinion must be held stationary and I therefore provide a detent, here shown as a 35 resilient rod b^{10} secured at one end to the main frame and having near its fore end a lug b^{11} which projects between teeth of the pinion B^4 . The end of the detent b^{10} projects into the path of segmental ribs b^{12} on the 40 surface of the wheel B^3 arranged in advance of the rows of teeth b^9 .

B^{10} is a mutilated gear wheel mounted on the shaft a^7 and intended to impart a vertical reciprocating motion to an ejector B^{11} 45 through the medium of a pinion b^{13} carrying a crank b^{14} , a crank lever b^{15} adjustably connected to the crank b^{14} and arms b^{16} attached at the upper end to a cross-head B^{12} to which the ejector B^{11} is attached. The cross-head 50 B^{12} at its ends engages with and is movable up and down on rods b^{17} extending upward from the table A .

C is a presser designed to coact with a die comprising horizontally movable portions C' , 55 C^2 , to cut and form the bunch. This presser C is movable vertically between side rails c^2 , and is actuated from the main shaft a^7 by the following means: Arms C^3 have a pivotal connection at one end with lugs on the presser 60 and at the other end are secured to a rock shaft C^4 having bearings in blocks extending upward from a frame or standards C^5 erected on the table A . From this rock shaft C^4 an arm c^4 extends and has pivoted to its outer 65 end a rod c^5 which at its lower end is pivotally connected to a rod c^6 pivoted at one end to a fixed portion of the frame and having at its

other end a roller c^7 which bears upon a cam c^8 mounted on the main shaft a^7 . Obviously a rotation of the cam c^8 with the main shaft 70 will impart a vertically reciprocating motion to the presser C . As a means for holding the roller c^7 in contact with the cam and render a positive motion of the presser, I employ a spring c^9 which is secured at one end to the 75 rod c^6 and at the other end to a fixed part of the frame A' .

I will now describe the horizontally operating forming die portions C' , C^2 . These die portions are supported by and are movable 80 toward and from each other on the support C^5 by means of the pitman B^7 , and its connections with the main shaft a^7 before described, which also impart a to-and-fro movement to the die frame B^8 . In the first operation the 85 die portions are moved toward each other to press the filler bunch before a forward movement is imparted to the frame B^8 carrying the die portions. To cause the die portions to approach each other I employ bell-crank levers 90 D , D' , which are respectively pivoted at their centers to the frame B^8 and are pivoted together at their adjacent ends as at d . One arm of the lever D is pivotally connected to a block d' which has a sliding connection with 95 frame B^8 and to which the pitman B^7 is attached. One arm of the lever D' is pivotally connected to a block d'' which has a sliding connection with frame B^8 as shown.

The operation of the parts above described 100 may be understood from the following: After the filler is fed between the die portions, by means hereinafter described, the rock-lever B^6 acts to cause the die portions to approach each other and press the filler between the die 105 portions as shown in Figs. 4 and 7. At a time just before the movement of the die portions the presser C is caused to move downward forming the top of the die as shown in Fig. 7. The continued motion of the rock-lever pushes the 110 male die, which is provided with a steel cutting edge half-way through the female die, which is provided with a cutting knife, as shown in Fig. 10, forward under the ejector B^{11} which now descends and forces the filler 115 into the loop e of a rolling apron E . This rolling apron E is secured at one end to the forward end of a bunching table E' on the carriage B' and extends over a bunching roller e' having journal bearings in the standards 120 C^5 and its opposite end is secured to a bar e^2 on the carriage B' . The lower plane of the bunching roller e' is but slightly above the plane of the bunching table E' so that loop e will be held closely around the filler dropped 125 into it, as in Fig. 8, when the table E' moves under the roller; a backward movement is imparted to the carriage B' and table E' at the proper time by the mechanism heretofore described and when the carriage shall have 130 reached the limit of its rearward movement, the completed bunch drops into the receptacle e^3 , from which it may be removed by hand. After the completion of the bunch as de-

scribed the carriage moves forward to its normal position, but before the carriage B' moves to roll the bunch the die portions have been returned to their normal position to receive 5 a fresh charge of filler from the feeder.

I will now describe the means for feeding the filler to the die; and also the means of controlling the length of the filler to be fed. This mechanism is best shown in Figs. 1, 11, 10 12, 13, and 14.

F, is a way for conveying tobacco, extending laterally from the bunching machine on a plane with the die portions C', C², and F', F², are endless carriers for conveying the filler 15 to the formers. The carriers are in the form of endless bands running in the way F, one carrier F², extending around rollers f, f', one of which is arranged adjacent to and in line with the entrance f⁵ to the die portions C', C² 20 and the other, f', has journal bearings in hangers at the outer end of the way F. This endless carrier F² runs in the way F. The carrier F' is shorter than the carrier F², and is arranged below the same and extends around 25 rollers f², f³, journaled in hangers depending from the way F. This short carrier F' has at convenient points fingers f⁴ extending from it at substantially right angles to the width of the carrier. These fingers are preferably 30 resilient and extend beyond the surface plane of the carrier F² and are designed to embrace the charge of filler at the sides to carry it along with the carrier F² as shown at F' and F² Fig. 11 of the drawings. The roller f³ over 35 which the carrier F' extends is at some distance from the entrance f⁵ to the dies so that there is a considerable space in which the fingers f⁴ do not aid in carrying the charge of filler over this space; however, I arrange 40 an endless presser band G. This band G, extends around rollers g, g', one of which has journal bearings in blocks g² which are vertically adjustable in ways g³. These blocks g² may be moved downward in the ways g³ 45 by means of screws g⁴ passing through threaded holes in the top plate of the ways g³ and springs g⁵ shown in Fig 16 of the drawings arranged beneath the blocks serve to raise them when the screws g⁴ are screwed upward. 50 The roller g' has its shaft bearing in the outer ends of adjustable bars g⁶, the other ends of which have a swinging connection with the journals of the roller g. A weight g⁷ at the end of a rod g⁸ suspended from one of the 55 bars g⁶ serves to hold the band G tightly against the upper side of the tobacco. Intermittent or step by step motion is imparted to the carriers, F', F², from the main shaft a⁷, by means of a mutilated gear G', rigidly 60 attached to the shaft a⁷ engaging at proper intervals with a pinion G² mounted on a shaft g⁹ and carrying a crank g¹⁰. A link G³ has an adjustable connection at one end with the crank g¹⁰ and at the upper end has a pivotal 65 connection with a rack G⁴ which is reciprocated vertically in a suitable guide-way erected on the table A. The rack G⁴ engages with

a toothed wheel H, which is loosely mounted on the extended shaft of the roller f. The wheel H is mounted loosely on the shaft so 70 that motion will not be imparted to the carriers F', F², during the downward movement of the rack G⁴, but to impart movement to said carriers during an upward movement of said rack I provide a ratchet wheel h which 75 is rigidly connected to the shaft of the roller f and the wheel H has attached to it a dog h' which engages with the teeth of the wheel h when the rack is moved upward and consequently rotary motion is imparted to the 80 roller f to move the carrier F². At the same time motion is imparted to the short carrier F' by means of a sprocket wheel h³ on the shaft of the roller f and with a sprocket-chain h² engaging with a sprocket-wheel h⁴ on the extended 85 journal of the roller f³. So it will be readily seen that by giving more or less throw to the rack G⁴ I regulate the length of the tobacco to be fed for a certain bunch. Motion is also imparted to the roller g', to move the band 90 G, from the shaft of the roller f, by means of a gear wheel h⁵, mounted on said shaft and engaging through intermediate automatically adjusting gears h⁶ with a gear wheel h⁷ mounted rigidly on the extended journal of the 95 roller g. The gears h⁶ have journal bearings in toggle links, h⁸, h⁹, h¹⁰, one of which, h⁸, is hung loosely on the journal of the roller g, and another of which, h¹⁰, is loosely connected with the shaft of the roller f, and the middle 100 one h⁹, being loosely engaged on the journals of the gears h⁶. By means of these toggle links the several gears, h⁵, h⁶, h⁷, will maintain their engagement at any adjustment of the roller g. 105

I will now describe the means of feeding the filler in equal quantities to the feed belts. I, is a plunger, movable on a table I', extended at right angles to and slightly above the way F and carriers F', F². This plunger I, has 110 rods I², extending rearward from it through bearings in a block I³, which are joined together at the outer ends by a hand bar I⁴. Springs i, are coiled around the rods I², between the plunger I, and the bearing block I³, 115 and serve to force the plunger I, forward; these springs are adjustable to give the desired pressure. A detent I⁵ serves to hold the plunger I, in its rearward position until it is desired to move the plunger forward. This 120 detent I⁵, consists of a resilient arm connected to the central portion of the plunger I, and having a lug i', which normally engages against the outer edge of a bar i², above the table I', as plainly shown in Fig. 11. This 125 arm I⁵, extends rearward within reach of an operator at the handle bar I⁴.

J, is a frame, open at opposite sides, into which filler is packed preparatory to feeding it to the machine. This frame J, when filled 130 by an operator with filler, is placed on the table I' forward of the plunger I, with its open sides so arranged that the plunger may pass into one side of the frame to force sufficient

filler out at the other side, into a chamber J' , directly above the carriers F', F^2 , the surplus filler remaining in the frame being cut off by means hereinafter explained. This chamber J' has a swinging bottom j , held in its normal horizontal position by means of springs j' which at their upper ends bear against the under side of the bottom j , and at their other ends extend into sockets j^2 below the table I' , and into which they are wholly depressed when the bottom j , is swung downward.

K , is an ejector for forcing tobacco from the chamber J' , onto the carrier F^2 , and at the same time cutting the surplus filler at the rear side along the front side of the frame J , thereby leaving the surplus filler in frame J . The ejector K , has rods k extending upward through guides k' , which are adjustable vertically on the parts k^2 to determine the thickness of the tobacco to be fed, thereby acting as a gage. That is, as the top of the ejector normally rests against the lower guide k' a vertical adjustment of this guide will limit the upward movement of the ejector out of the chamber J' , and consequently modify the outlet of the frame J . The chamber J' , has a side wall j^4 , which is rendered adjustable toward and from the opposite side of the chamber, secured to a carrier I' , which is movable on the table I' and also carries the plunger I , by means of rods j^5 , secured to it and projected through holes in a side j^6 , of the way F , and secured as adjusted by set screws j^7 passing through tapped holes in collars j^8 , secured to said side. A hand bar K' , joins the upper ends of the rod k , and springs k^3 , surrounding said rods between the hand bar K' , and the upper guides k' serve to return and normally hold the ejector in its upward position. The ejector K has a yielding lower side k^4 . This lower side consists of a metal plate L shaped in cross-section, the upright portion of which slides against the outer side of the ejector as shown in Fig. 11; and the horizontal portion has pins k^5 extending into vertical openings in the ejector in which are seated coiled springs k^6 . The ejector carries a cutter blade L , which when the ejector is moved downward cuts the filler evenly at the side along the front opening of the frame J . The surplus filler remaining in the frame, may have more filler added to it to the proper amount, if found necessary. The operation of this part of the machine is as follows: The tobacco is first placed in a frame J , and this frame is placed in position forward of the plunger I ; the operator now pulls upward the detent I^6 , allowing the springs i , to move the plunger through or into the frame J , and force the charge of filler into the chamber J' . Now the operator forces the ejector downward to cut the filler and eject it onto the carrier F^2 , which transfers it to the dies as before described.

65 Returning now to the forming die portions C', C^2 , I will describe means for cutting the

tobacco bunch into proper lengths and at the same time forming the point end of the cigar.

The die portion C' is provided at its upper side for a portion of its length with a cutter p , and the die portion C^2 is provided on its upper side with a similar cutter p' , and a stationary cutter p^2 , is fixed to the bed plate P , upon which the die frames move. After tobacco from the feeder shall have been fed between the die portions and the presser C shall have assumed its downward position, the die portion moving together will cause the several cutters to cut the bunch as indicated by the dotted line p^4 , Fig. 15, so that the part P' has the general form of a cigar. After this part, P' , shall have been forced into the roller apron as before described, the bunch is again fed forward, and its bifurcate end, formed by the cut on the line p^4 , will be closed together, so that there is no waste.

Having described my invention, what I claim as new in a cigar-bunching machine is—

1. The combination with driving mechanism of two horizontally movable die portions, a vertically moving presser coacting with the die portions, a gear and lever mechanism between said driving mechanism and die portions and a mutilated gear adapted to impart intermittent half-revolutions to said first named gear and reciprocate the die portions, substantially as specified.

2. The combination with driving mechanism of two horizontally movable forming die portions, mechanism substantially such as described for causing the movements of said die portions, a vertically moving presser, coacting with the die portions, means for operating said presser, an ejector for forcing the filler from the die portions, and a roller apron, onto which filler is forced from the die, substantially as specified.

3. The combination with driving mechanism and a horizontally movable forming die, of two endless carriers driven from a main shaft, one arranged below the other, and the said lower carrier having upwardly projecting fingers extending above the upper carrier, to engage the sides of the filler, substantially as specified.

4. In combination with a horizontally movable die and mechanism for operating the same, of an endless carrier, a toothed wheel on one of the rollers of said carrier, a vertically operating rack engaging with said toothed wheel and a mutilated gear and intermediate mechanism for operating said rack, substantially as specified.

5. The combination with a horizontally movable forming die of the endless carriers, one arranged below the other, the lower carrier having upwardly projecting fingers extending above the upper carrier, mechanism comprising a rack and toothed wheel, said rack having connection with a main shaft

and an endless presser band arranged above a portion of one of said carriers at its discharge end, substantially as specified.

6. The combination with a horizontally movable forming die and mechanism comprising a main shaft for operating the same, of endless carrier one arranged below the other, the lower carrier having upwardly projecting fingers, extending above the upper carrier, 5 said carriers operated with an intermittent motion from said main shaft, an endless presser band above a portion of one of said carriers, rollers over which said presser band extends, an adjustable connection between said rollers and a weight for forcing said presser band toward the carrier, substantially as specified.

7. The combination with a horizontally movable forming die and mechanism for operating the same, of endless carriers one arranged below the other, the lower carriers having upwardly projecting fingers extending above the upper carrier, a rack mechanism for operating the same, a main shaft, connection 20 between the shaft and rack, an endless presser band, a roller over which said presser band extends, a yielding bearing for said roller, a gear wheel on the shaft of a roller of one of the carriers and automatically adjustable gear wheels 25 connecting said first-named gear wheels, substantially as specified.

8. The combination with a former die and a carrier, of a plunger for forcing tobacco into a chamber above said carrier and an ejector 30 for forcing the tobacco from said chamber onto the carrier, substantially as specified.

9. The combination with a former die and a carrier, of a plunger operating at right angles to the movement of said carrier, a chamber above the carrier having a yielding bottom and an ejector for forcing tobacco from 40 said chamber onto the carrier, substantially as specified.

10. The combination with the former and the carrier of a chamber above said carrier, a plunger for forcing tobacco from a frame into said chamber, springs for moving said plunger forward and an ejector for forcing tobacco from the chamber onto the carrier, 45 substantially as specified.

11. In combination with a forming die and carrier mechanism of a chamber arranged

above said carrier, a plunger for forcing tobacco from a frame into said chamber, an ejector movable through said chamber and a 55 cutter blade carried by said ejector, substantially as specified.

12. The combination with a carrier, of a chamber above said carrier, a plunger for forcing tobacco into said chamber, rods extending rearward from said plunger, springs for moving the plunger forward, a detent for holding it in its rearward position, and an ejector movable vertically through said chamber, substantially as specified. 65

13. The combination with a forming die and a carrier, of a plunger for forcing tobacco into a chamber above the carrier the chamber and an ejector movable through the chamber and having a yielding bottom plate, substantially 70 as specified.

14. In combination with a forming die and a carrier, of a plunger for forcing tobacco into a chamber above the carrier, the chamber an ejector movable through said chamber and a 75 spring or springs for moving said ejector in one direction, substantially as specified.

15. The combination with a former and a carrier, of a chamber arranged above said carrier, of a plunger for forcing tobacco into said 80 chamber, an adjustable side and swinging bottom for said chamber and an ejector operating vertically through said chamber, substantially as specified.

16. The combination with driving mechanism, comprising a main shaft, of a forming die operated from the main shaft, a presser coacting with the die and operated from the main shaft, an ejector for forcing the tobacco from the die and operated from said main 90 shaft and a bunching mechanism to which the filler is forced by the ejector, substantially as specified. 85

17. The combination with driving mechanism of horizontal operating die portions each 95 portion having for a portion of its length a cutter, a fixed cutter on the bed plate coacting with the first named cutters, substantially as specified.

JOSEPH DELA MAR.
